UNITED STATES PATENT OFFICE.

LOUIS H. WILKINSON, OF MERIDEN, CONNECTICUT, ASSIGNOR TO MANNING, BOWMAN & COMPANY, OF MERIDEN, CONNECTICUT, A CORPORATION OF CONNECTICUT.

PERCOLATOR CONSTRUCTION.

1,116,962.

Specification of Letters Patent Patented Nov. 10, 1914.

Application filed November 13, 1913. Serial No. 800,708.

To all whom it may concern:

Be it known that I, LOUIS H. WILKINSON, a citizen of the United States, residing at Meriden, New Haven county, State of Connecticut, have invented certain new and useful Improvements in Percolator Construction, of which the following is a full, clear, and exact description.

This invention relates to an improvement in the construction of percolator pots and more particularly to means for feeding the liquid from the main body of the pot to the heating chamber at its base whereby the liquid in said chamber may be quickly heated and forced up the percolator tube and as quickly replaced by fresh liquid from the main pot body. These and other advantages will be more clearly apparent from the following detailed description taken in connection with the accompanying drawings forming part thereof and illustrating structural embodiments of the invention.

In the drawings, Figure 1 is a fragmentary sectional view illustrating as much of a percolator pot and its heating chamber and tube as is necessary to disclose an embodiment of the present invention. Fig. 2 is a top plan view of the parts shown in Fig. 1. Figs. 3, 4 and 5 are details of construction. Fig. 6 shows in vertical section a different form of tube and plug having a modified form of valve applied thereto. Figs. 7 and 8 respectively are top and bottom plan views of the parts shown in Fig. 6. Figs. 9 and 10 are views of details of the modified construction of valve.

In the drawings, 1 designates the portion of the body of a percolator pot at its bottom to which the usual heating base 2 is secured by means of a nut 3. This heating base is hollow and is provided with a heating chamber 4 therein designed to receive and heat liquid fed thereto from the body of the pot. This heating base below the chamber 4 has an enlargement or disk 5 designed to rest adjacent a source of heat, the enlargement increasing the heating surface and the heat therefrom being conducted directly to the heating chamber 4 as is usual in this type of pot.

6 denotes the usual percolator tube, preferably thickened adjacent its lower end as at 6' to form a strong construction, the lower end of this tube extending through a hollow

thereto as by sweating. This plug has the usual flange 7' at its upper end and is preferably slightly tapering to fit snugly within the heating chamber 4, the bottom of the plug being spaced substantially above the bottom of the heating chamber and the plug serving to some extent to insulate the heating chamber from the body of the pot, as usual. One or more tubes 8 extend through the plug with their upper and lower ends communicating respectively with the main body of the pot above the plug and the heating chamber below the plug, this tube or tubes serving as means for conducting liquid from the main body of the pot to the heating chamber. In order to control the flow of liquid from these feed passages, I provide the following valve construction. The lower enlarged end 6' of the tube is preferably flush with the bottom face of the plug 7. This lower end is interiorly threaded as at 9 and is designed to receive the upper threaded end of a hollow tube 10, which tube is provided with a stop shoulder 12 at the end of the sweated portion, which stop shoulder engages the end of the percolator tube and spaces a second shoulder 13 from the lower end of this tube and from the bottom face of the plug. This second shoulder 13 forms a seat for a valve disk 14 which is seated over the tube 10 and on its shoulder when the upper threaded end 11 of the tube is screwed into the lower end of the percolator tube. This valve disk is of sufficient diameter to cover fully the openings from the inlet passages at the bottom of the plug, and the thickness of this disk relative to the distance between the shoulders 12 and 13 is such as to permit movement of the disk toward the tubes 8 to close the same and away from said tubes to open the same and permit water to flow into the heating chamber. The valve disk 14, being guided and retained on the tube, will normally tend to rest on the shoulder 13 through gravity, permitting liquid from the main body of the pot to enter the heating chamber through the feed tubes 8. Assuming that the heating chamber 4 has been filled with liquid and the same is being heated, the pressure generated in the chamber through the heating of the liquid will force the valve disk 14 up against the openings of the tubes 8, closing the same and preventing further flow of liquid from the pot body into the heating

chamber until the heated liquid has ascended the percolator tube in the usual manner. The hollow tube 10 forms in effect a portion or continuation of the percolator tube below the plug so that as the liquid becomes heated, it will rise through the tube 10 and through the percolator tube 6 in the usual manner. When the pressure in the heating chamber drops through the discharge of the heated liquid therein, fresh liquid from the main pot body will enter through the tubes 8 and will again fill the heating chamber and be heated, the valve disk 14 rising and closing the inlet openings as before and the process continuing in this manner. The valve disk 14 being of substantial area is readily controlled by the action of the heated liquid in the heating chamber and will readily respond to fluctuations in the pressure within said chamber so that liquid from the main pot body will be fed into the heating chamber whenever the pressure therein drops any substantial amount. This will enable the heating chamber to be continually filled with liquid and to have a continuous supply of fresh liquid from the main reservoir or pot body fed thereto as the contents of the heating chamber are ejected therefrom in quantities insufficient to exhaust the capacity of the heating chamber. This it will be seen will maintain a heated body of liquid in the heating chamber at all times as it is not necessary to eject the entire contents of the heating chamber before more liquid can be fed thereto.

The form of plug heretofore described is particularly adapted for percolator pots of the type wherein the heating medium is separate from the pot body. When the heating medium is carried by the pot body, as in the case of an electric percolator, a slightly different form of plug is employed and preferably a slightly different form of valve construction. In Figs. 6 to 10 I have shown such a form of plug and valve construction. Referring specifically to these figures of the drawing, 6^b designates the percolator tube having an enlarged lower end 6^c as by sweating thereon another tube. The inner tube 6^b extends through a hollow plug formed of complementary disks 15—16 united at their outer edges, the disk 15 being provided with a central boss 15^a. Adjacent this boss the disk 15 is countersunk and hollow tubular rivets 17 are inserted to secure the inner and outer disks together at this point and also to provide a liquid feed passage through the hollow rivets whereby liquid may be fed from the main pot body to the heating chamber. It is unnecessary to describe herein the detailed construction of the base of an electric percolator inasmuch as it is well known in the art, the hollow plug formed by the disk 15—16 seating within a heating chamber 65 formed in the base of the pot body in a man-

ner similar to that shown and described in connection with Fig. 1 of the drawings. The under disk 16 is dished inwardly and upwardly to provide a space for a controlling valve for the inlet opening 17. To this end 70 the percolator tube 6^b extends below the under face of disk 15 and has its lower end exteriorly threaded to receive a sleeve 18 having its interior correspondingly threaded and provided at its lower end with an annular inset flange 19 designed to engage the lower end of the percolator tube 6^b and limit the upward movement of the sleeve 18 thereon so as to position the upper edge of said sleeve the proper distance below the lower 80 ends of the inlet opening 17. Before the sleeve 18 is applied to the lower end of the percolator tube, a valve disk 20 is seated over said tube end and rests on the upper edge of sleeve 18 as the latter screws up on the 85 percolator tube. The flange 19, when it engages with the lower end of the percolator tube, positions the valve disk 20 so that when resting on the upper edge of the sleeve 18, it is away from the inlet opening 17 and will 90 permit liquid to flow from the main pot body into the heating chamber below the plug. When, however, sufficient pressure has been generated in the heating chamber because of the heated liquid therein, the 95 valve disk 20 will be lifted to close these inlet openings until the pressure has been diminished by the heated liquid rising in the percolator tube, whereupon the valve disk will drop and admit sufficient water from the 100 main pot body to continue the heating operation as heretofore described. It will be, of course, understood that the thickness of the valve disk 20 relative to the distance between the upper edge of the sleeve 18 and the lower 105 ends of the tubular rivets 17 will be regulated to permit this upward and downward controlling movement.

While I have herein described a preferable embodiment of my invention, I desire it understood that various changes in structure and in the relative arrangement of parts are still possible within the spirit of the invention and the scope of the appended claims.

What I claim, therefore, and desire to secure by Letters Patent is:

1. In a percolator, the combination of a main chamber, a heating chamber at the base thereof, a percolator tube, a plug carried thereby adjacent its lower end adapted to seat in said heating chamber and closing the space between said main and heating chambers, said tube extending through and below said plug and into said heating chamber, 120 said tube having a valve supporting seat thereon below the under face of said plug within said heating chamber, said plug having a liquid inlet passage therethrough communicating directly with said main and heat- 130

ing chambers, and a disk valve supported on said tube seat below said plug and within said heating chamber and in line with said liquid inlet passage, said disk sliding freely 5 on said tube to open and close said passage.

2. In a percolator, the combination of a main chamber, a heating chamber at the base thereof, a percolator tube, a plug carried thereby adjacent its lower end adapted 10 to seat in said heating chamber and closing the space between said main and heating chambers, said tube extending through and below said plug and into said heating chamber, said tube having a valve supporting seat 15 thereon below the under face of said plug within said heating chamber, said plug having a liquid inlet passage therethrough communicating directly with said main and heating chambers, and a disk valve supported on 20 said tube seat below said plug and within said heating chamber and in line with said liquid inlet passage, said disk sliding freely on said tube to open and close said passage, and being of substantial area relative to the 25 cross section of the heating chamber.

3. In a percolator, the combination of a main chamber, a heating chamber at the base thereof, a percolator tube, a plug carried thereby adjacent its lower end seating in said heating chamber and closing the space be- 30 tween said main chamber and said heating chamber, said percolator tube extending through said plug and having a tubular sleeve section secured to its lower end and positioned below said plug and within said 35 heating chamber, said section having thereon a valve supporting shoulder spaced from the under face of said plug, said plug having a liquid inlet passage therethrough communicating with said main and heating cham- 40 bers, and a disk valve normally resting on the supporting shoulder of said section in line with said liquid inlet passage and of substantial area relative to the cross section of said heating chamber.
